UNITED STATES PATENT OFFICE

152,819

DESIGN FOR A VEHICLE FRAME

Roy A. Noble, Lewiston, and Wallace I. Youngs,
Buffalo, N. Y., assignors to Bell Aircraft Corporation,
Wheatfield, N. Y.

Application February 5, 1947, Serial No. 136,698

Term of patent 14 years

(Cl. D14—3)

To all whom it may concern:

Be it known that we, Roy A. Noble and Wallace I. Youngs, citizens of the United States, residing at Lewiston, in the county of Niagara and State of New York, and Buffalo, in the county of Erie and State of New York, respectively, have invented a new, original, and ornamental Design for Vehicle Frame, of which the following is a specification, reference being had to the accompanying drawing, forming part thereof.

Fig. 1 is a side elevational view of a vehicle frame, showing our design;

Fig. 2 is a top plan view thereof;

Fig. 3 is a front end elevational view thereof; and

Fig. 4 is a rear end elevational view thereof. The dotted line showing in the several drawing figures is for illustrative purposes only.

We claim:

The ornamental design for a vehicle frame, as shown and described.

ROY A. NOBLE.
WALLACE I. YOUNGS.
